UNITED STATES PATENT OFFICE.

HUGH WARREN LEE AND JOHN WINDLOW SWINDALE, OF NEWCASTLE-UPON-TYNE, ENGLAND, ASSIGNEES TO SIR W. G. ARMSTRONG, WHITWORTH AND COMPANY, LIMITED, OF NEWCASTLE-UPON-TYNE, ENGLAND.

HOIST ESPECIALLY SUITABLE FOR RAISING PROJECTILES ON BOARD SHIP.

Application filed April 26, 1923. Serial No. 634,714.

To all whom it may concern:

Be it known that we, HUGH WARREN LEE and JOHN WINDLOW SWINDALE, subjects of the King of Great Britain, residing at 5 Elswick Works, Newcastle-upon-Tyne, England, have invented a new and useful Improvement in Hoists Especially Suitable for 10 Improvement in Hoists Especially Suitable for Raising Projectiles on Board Ship, of which the following is a specification.

15 This invention relates to hoists in which a load is raised by means of two sets of lifting arms carried by two bars which are raised and lowered alternately, the arms on each bar being turned into their operative position as that bar rises and being turned out of their operative position as the bar falls, so that the load is raised by an arm on one bar, then by an arm on the other bar, then by a second arm on the first 20 bar, and so on.

According to this invention the two bars are raised and lowered by two hydraulic rams working in two fixed cylinders and connected one to each bar, preferably by 25 crossheads, and the two bars are coupled together by their being connected to an endless chain passing over two fixed sprocket wheels, so that the rise of one bar consequent on the admission of pressure water to its 30 cylinder causes the descent of the other bar and the expulsion of the water from its cylinder. The admission of pressure water to the two cylinders alternately may be effected by a valve actuated by a tappet on 35 one of the bars. The arms are turned into and out of their operative positions by means of a cam plate which has in it slots in which move fingers or cams pivoted on the bars and which are so shaped that the 40 fingers or cams are turned on their pivots at or near to the ends of the strokes of the bars. The cam plate may be provided with means whereby the normal motion of the arms may be reversed should it be desired 45 to lower a load instead of raising it, that is, whereby the arms may be put into their operative position when the bars are descending instead of when the bars are rising.

The invention is illustrated by the accompanying drawings, in which Figure 1 is a

side elevation of the lower part of the mechanism and Figure 2 a side elevation of the upper part; Figures 3 and 4 are views at right angles to Figures 1 and 2. Figure 5 is a detail of the valve controlling the admission of water to the cylinders and of the means for actuating that valve. Figures 6 and 7 are detail views of the cam plates and fingers.

A, A¹, are two cylinders in which move rams B, B¹, the ends of which are connected by crossheads C, C¹, to bars D, D¹. The two crossheads are also connected to opposite sides of a chain E which passes over two fixed sprocket wheels F, f. The lower end of each ram carries a piston G which fits watertight to its cylinder. Water can be admitted to the bottoms of the cylinders by pipes H, H¹, and to the top of each cylinder by pipes J, J¹, these pipes leading from a valve chest K having in it a valve L. The valve rod l is connected to two arms l², l³, on fixed pivots, and the bar D carries a tappet d so arranged that when the bar D reaches the bottom of its stroke the tappet comes against the arm l² and turns it downwards, thus bringing the valve L into the position shown in the drawing and admitting pressure water to the bottom of cylinder A so that the bar D will now be raised. As the bar D reaches its topmost position tappet d comes against arm l³ and turns it up, thus reversing the valve L, putting pipes H, J¹, to exhaust and admitting pressure to pipes J and H¹, so that ram B¹ will be raised and as it rises it will through the chain E cause the ram B to descend, this descending movement being also assisted by the admission of pressure water through pipe J to the annular space between the ram B and its cylinder. To each of the bars D, D¹, is pivoted a number of lifting arms M: each arm has on it a projection m engaged by a rod N, the top end of which is connected by a link n to an arm m¹ fast with three fingers pivoted to the lifting bars D, D¹, respectively. The fingers move in slots O, O¹, formed in a cam plate P in guides p on which can move two plates Q, R, actuated by bell cranks q, r connected together by a link S.

Figure 6 shows the parts when lifting is taking place, that is, when the lifting arms M project as shown in Figure 3 into the trunk on each upward movement of the bar 5 to which they are connected but are withdrawn from the trunk on the downward movement.

- Consider the fingers on the right hand bar D. The fingers T, T¹, are in the plane of 10 the slot O while the finger T² is outside the slot. As the bar D rises with the fingers in the positions shown in slot O in Figure 6, when the bar reaches the top of its stroke, finger T comes against a projection Q¹ on plate Q 15 and the fingers are thereby turned as seen in slot O¹. Thereupon the bar begins to descend and finger T¹ comes against an incline O² in the side of the slot O and the fingers are thereby still further turned as shown in 20 slot O¹. The rod N is thereby moved relatively to the bar D and the lifting arms M carried by that bar are therefore turned on their pivots and withdrawn from the trunk. When the bar D reaches the bottom of its 25 travel finger T comes against a projection R¹ carried by plate R and the fingers are thereupon turned in the opposite direction so that the lifting arms M are caused to project into the trunk.
- 30 Should it be desired to lower projectiles down the trunk the bell crank q is moved counter-clockwise as seen in Figure 2 with the result that plates Q and R are moved to the left. Therefore the projections carried 35 by plates Q and R leave the positions in which they are shown in Figure 6 and assume the positions in which they are shown in Figure 7, with the result that on bar D reaching its lower position its finger T¹ 40 comes against projection R² and the fingers are thereby turned counterclockwise as seen in the bottom right hand corner of Figure 7. Similarly, when D¹ arrives at the bottom of its stroke its finger T¹ will come against the 45 left hand side of projection R¹ and will similarly be turned. Therefore during the ascending movement of either bar the lifting arms carried by it will be withdrawn from the trunk. As the bar D nears the top of its 50 stroke its finger T² will come against projection Q² on plate Q so that the fingers will be turned clockwise into such a position that as the bar continues to rise finger T¹ enters recess O² whereupon the fingers are further 55 turned clockwise until they assume a position corresponding to that of the fingers in slot O¹ of Figure 7. It will be understood that owing to the movement of plate Q its projections Q¹ will have been moved out of 60 their operative positions shown in Figure 6 into the positions shown in Figure 7 in which they are out of the path of the fingers. The result of the turning movement of the fingers is to cause the lifting arms to protrude 65 into the trunk so that they can support a pro-

jectile in their descent. When the bar reaches the bottom of its travel the fingers will be withdrawn as before described by the finger T¹ striking the projection R² or R¹ as the case may be.

What we claim is:—

1. In a hoist, the combination of a pair of bars, lifting arms pivoted to each bar, a pair of hydraulic rams, one connected to each bar, two fixed sprocket wheels, a chain passing round the wheels and connected to the two bars and means for turning the arms on their pivots. 70

2. In a hoist, the combination of a pair of bars, lifting arms pivoted to each bar, a pair of hydraulic rams, one connected to each bar, two fixed sprocket wheels, a chain passing round the wheels, and connected to the two bars, means for turning the arms on their pivots, a valve adapted to control the supply 75 of liquid to the rams and means whereby one of the bars on arriving at the end of its travel in either direction reverses the valve. 80

3. In a hoist, the combination of a pair of bars, lifting arms pivoted to each bar, a pair of hydraulic rams, one connected to each bar, two fixed sprocket wheels, a chain passing round the wheels and connected to the two bars and means for turning the arms 85 on each bar into their operative positions 90 when that bar is rising and into their inoperative positions when that bar is descending. 95

4. In a hoist, the combination of a pair of bars, lifting arms pivoted to each bar, a pair of hydraulic rams, one connected to each bar, two fixed sprocket wheels, a chain passing round the wheels and connected to the two bars, means for turning the arms on each 100 bar into their operative positions when that bar is rising and into their inoperative positions when that bar is descending and means for reversing the positions of the arms. 105

5. In a hoist, the combination of a pair of bars, a pair of hydraulic rams, one connected to each bar, two fixed sprocket wheels, a chain passing round the wheels and connected to the two bars, lifting arms pivoted to each bar, a rod connecting the arms of each bar, fingers pivoted to the bars, a cam 110 plate adapted to turn the fingers on their bars and means whereby the turning of the fingers on either bar moves the rod relatively 115 to the bar.

6. In a hoist, the combination of a pair of bars, means for moving them up and down alternately, lifting arms pivoted to each bar, a rod connecting the arms of each bar, fingers pivoted to each bar and connected to the rod thereof and a cam plate adapted to 120 turn the fingers of each bar near the end of the travel thereof and so to move the rod of that bar relatively to that bar. 125

7. In a hoist, the combination of a pair of bars, means for moving them up and down. 130

alternately, lifting arms pivoted to each bar, a rod connecting the arms of each bar, fingers pivoted to each bar and connected to the rod thereof, a cam plate adapted to turn the fingers of each bar near the end of the travel thereof and so to move the rod of that bar relatively to that bar and means where-

by the normal movements of each rod relative to its bar can be reversed.

In testimony that we claim the foregoing as our invention we have signed our names this 26th day of March, 1923.

HUGH WARREN LEE.
JOHN WINDLOW SWINDALE.
